CONVECTION CURRENT MOTOR

Earl R. Roach, Springville, Ind.

Application November 3, 1934, Serial No. 751,431

1 Claim. (Cl. 253—38)

This invention relates to motors deriving power from convection currents.

One of the objects of the invention is to provide for utilizing the power present in the flow of combustion products from furnaces for developing a certain amount of power.

Another feature of the invention is to automatically control the speed of a motor by the velocity of the air entering the flue chamber.

10 Further objects of the invention are to provide a motor of the character referred to that is strong, compact and durable, thoroughly reliable for its intended purpose, very easily adapted to large manufacturing plants that use furnaces and ovens, that is very simple to install and requires very little repair after installation.

With the foregoing and other objects in view the invention consists in the novel construction, combination and arrangement of parts as will be hereinafter more specifically described and illustrated in the accompanying drawings and specification, but it is to be understood that changes, variations and modifications may be resorted to without departing from the spirit of 25 the claim hereunto appended.

In the drawings wherein like reference characters denote corresponding parts throughout the several views:

Figure 1 is a fragmentary, top plan view of the 30 device in accordance with the present invention assembled on a flue chamber,

Figure 2 is a side elevation thereof,

Figure 3 is an enlarged, detailed vertical section thereof,

35 Figure 4 is a fragmentary vertical section taken substantially on line 4—4 of Figure 2,

Figure 5 is a detailed vertical section taken substantially on line 5—5 of Figure 3 and looking toward the flue chamber,

40 Figure 6 is a horizontal section taken substantially on line 6—6 of Figure 7 and looking in the direction of the arrows,

Figure 7 is a vertical section through the top of one of the vats taken substantially on the line 45 1—1 of Figure 2,

Figure 8 is an enlarged detailed horizontal section taken through the governor.

In the preferred embodiment of my invention it is feasible in large factories using large furnaces, ovens and boilers in a segregated area to construct a common flue to carry off the waste gases. In the drawings, I have shown a portion of this main discharge flue indicated at 9. The flue may be of any area consistent with the 50 amount of combustion products to be carried off

from the furnaces and ovens, and in the preferred form I make the flue rectangular in configuration with the path of the combustion products discharging parallel to the surface of the earth. The flue 9 rests on a very sound 5 concrete foundation 10 that is preferably submerged below the frost line to overcome contraction and expansion.

In the flue I provide vertically spaced braces 10 to aid in supporting the chimneys or stacks. 10 To vent the flue chamber 11 the top wall 12 thereof is formed with upstanding flanges of suitable strength indicated at 13. The plurality of chimneys or stacks 14 have their lower ends secured in an air tight manner in the upstanding 18 flanges 13. The passages 15 in the stacks or chimneys are disposed at right angles to the path of the combustion products in the flue chamber 11. Any number of chimneys or stacks may be used to vent the flue chamber to the 20 atmosphere and very good results have been obtained by making the height of the stacks or chimneys approximately 50 feet.

The upper end of the chimneys 14 are baffled by a dome or cap 16, which cap is supported on 25 four U-shaped brackets 17, and one leg of the bracket is secured to the upper margin of the stacks or chimneys while the other leg is secured to the cap or dome. The lower opened end of the cap or dome 16 is below the upper end of the 30 chimney so as to baffle the outgoing product of combustion from the chimney. There is one dome for each chimney.

In the arrangement of the present invention it is to be seen that the flue gases from the furnaces, ovens and other heating plants shall pass from right to left with respect to Figure 3 of the drawings and up through the plurality of chimneys 14, the passages of which are disposed at right angles to the path of the outgoing 40 gases. In combining my motor there is formed an opening 18 in an end wall 19, which latter I select the farthest away from the source of heat. About the opening there is an outset flange 20 to which is attached the inner end of a horizontally disposed air drum 21. The air drum 21 is open as at 22 on its free outer end. Air drum 21 rests on a pair of spaced foundation blocks 23 to which are bolted the steel straps 24 that encircle the upper portion of the air drum. The foundation blocks 23 rest upon the main foundation 10. It will be seen that the passage of cold air through the drum chamber 25 is in direct opposition to the flow of the hot gases within the flue chamber 11. The path of the cold air 55

- through the drum chamber is parallel to the path of the hot gases in the flue chamber and the former path is indicated by the arrows in Figure 3 of the drawings.
- In the outer end of the drum 21 is mounted the drive shaft 26. Drive shaft is journalled at two places in the hubs 28 of a pair of ring bearing supports 27. Ring bearings 27 are disposed diametrically across the drum 21 and are horizontally spaced from each other. The shaft is disposed co-axial with respect to the drum 21. Between the bearings the impeller wheel A is fixed to the shaft 26 and lies within the drum chamber 25 diametrically across the path of flow of the cold air.
- The impeller wheel A conformably fits within the drum 21 so as to move therein without having friction between the inner walls of the drum and yet utilize all the power of the cold air passing through the blades. The impeller consists of a solid rim 29 and a hub 30 connected together by solid radial ribs 31. Between the ribs 31 are a plurality of substantially rectangular openings 32 across which are disposed the fins or blades 33.
- A portion of the shaft 26 extends beyond the open end 22 of the drum and is formed at its terminal with a drive pulley 34 and another governor pulley 35. The inner end of a pair of journal brackets 36, 37 are secured to the side walls 30 of the drum 21. In the brackets 36, 37 is journalled the drive shaft 38 of the governor B. On the outer end of the governor shaft 38 is a pulley 39 about which is trained a belt 40 to transmit motion from the impeller shaft to the governor shaft. Adjacent the outer bearing bracket 36 is fixed a collar 41 and adjacent the other bracket 37 is a movable collar 42 and both collars are on the governor shaft 38. Abutting the movable collar 42 is one end of a coil spring 43 which encircles the governor shaft 38 and is held in position by the bushing 44 fixed to the governor shaft. There are two flexible metal straps 45 having their opposite ends secured to the perimeters of the respective collars 41, 42 and fastened to the centers of the flexible straps are the weights 45'. Thus when the governor shaft 38 overcomes the tension of spring 43 the weight 45' moves outwardly by centrifugal force and moves collar 42 outwardly.
- In the collar 42 is a channel race 46 in which is movably seated a ring or collar 47 to which is attached the outer end of the damper operating lever 48.
- A damper shaft 49 is mounted in the drum chamber 21 and is journalled in the diametrically opposite walls of the drum. The shaft 49 carries the control damper 50 and the shaft 49 is connected by the arm 51 to the lever 48. Mounted on top of the drum are a pair of oil reservoirs 52 one for each of the drive shaft bearings 28 and leading from the oil reservoirs are a pair of conductor pipes 53 which convey the oil to the bearings.
- It will be seen that when the drive shaft 26 reaches a predetermined speed the governor will close damper 50 which will baffle the incoming cold air to the flue chamber 11.
- Although I have shown and described my motor as being particularly adaptable to the flue 9 leading from furnaces, ovens and other heating plants, it is to be understood that my motor 20 will operate from natural draft. In this event, I may make the flue 9 in the form of a substantially rectangular casing and mount the chimneys 14 on the rectangular casing. Then, the air drum 21 will be mounted on the rectangular 25 casing similar in all respects to the mounting on the flue 9 as shown in the drawings. In order to obtain maximum efficiency it is necessary to have considerable weight in the impeller wheel A. Very good results may be had by making the 30 impeller wheel A three inches thick, although I do not wish to confine myself to this particular thickness.
- Having described my invention what I claim as new is:
- A device of the class described, comprising an air drum, open at each end thereof, a pair of spaced bearing supports mounted on the interior of said drum having centrally disposed bearing blocks therein, a shaft rotatably mounted in said bearing block, said shaft extending beyond one end of said drum, an impeller secured to said shaft between said supports, means on the exterior of said drum communicating with said bearing block for lubricating said bearing block, a pulley on the 45 extended portion of said shaft, a pivotally mounted damper in said drum, and a governor for actuating said damper, and means connecting said pulley with said governor for rotating the same.

EARL R. ROACH.
